UNITED STATES PATENT OFFICE

LOUIS KRUPP, OF BROOKLYN, NEW YORK

MIRROR ATTACHMENT FOR HAND BAGS

Application filed September 20, 1929. Serial No. 394,040.

This invention relates to hand bags and the like, and more particularly to an adjustable mirror attachment therefor.

Mirrors have usually been carried loosely in hand bags so that the user has been obliged to hold both the loose mirror and the bag in one hand while using the other hand for application to the face or hair in various ways, an arrangement that has been generally inconvenient. Mirrors have also been provided on flaps secured to the inner side of the bag frame, and in such cases the same disadvantages have existed, in that the flap had to be held up to position the mirror for use.

15 The primary object of my invention is to enable a mirror to be adjustably mounted within the bag so that the mirror can be swung automatically to an elevated position outside the bag frame.

20 A further object is to provide spring actuated means to operate the mirror, such spring actuated means being controlled by the movement of the bag frame members themselves.

25 A still further object is to provide a spring actuated device which is caused to be set during the closing movement of the bag frame members and which can be released to expel the mirror by manual means while the bag is open, so that the bag can be opened for ordinary use without expelling the mirror; also so that the mirror can be manually released and swung to use position by spring actuated means while the bag is open the normal distance.

35 Another object of the invention is to provide a spring plunger on one of the frame members to operate the mirror carrying link and to enable said plunger to be actuated by a cam device associated with the opposite frame member, preferably at the hinge portion of the bag.

40 Still another object is to enable the spring plunger to be normally held in place by a pin and slot device and to be released manually to project the mirror while the bag is open; and another object is to enable the mirror to be automatically withdrawn from its elevated position to a position within the bag by the

closing action of the bag frame members themselves.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawings, which latter show an embodiment of the invention as at present preferred.

In the drawings:—

Fig. 1 is a partial elevation of the interior of the bag frame members partly opened, showing the mirror in its normal rest position within the bag.

Fig. 2 is a view similar to Fig. 1 showing the mirror projected from the bag to an elevated position.

Fig. 3 is an interior end view showing the position of the operating means at the commencement of the opening movement of the bag.

Fig. 4 is a view similar to Fig. 3 showing the operating means in the position assumed when the bag is open.

Fig. 5 is a sectional view of the mirror on the line 5—5 of Fig. 2, showing its means of attachment to the swinging link.

Referring more particularly to the drawings, the hand bag 10 in this instance includes a pair of U-shaped frame members 11 and 12 hinged at 13.

To support the mirror within the bag frame, I provide a short bracket arm 14 at the upper part of the U-shaped frame member 11. A mirror carrying link member 15 is pivotally secured intermediate its length to the end of the bracket arm 14, as seen at 16. This link member 15 has a suitable mirror 17, secured to one of its ends. In this instance, the back 18 of the mirror is formed with a suitable groove or slideway 19 so that the end of the link member 15 can be inserted in the back of the mirror, by which means the mirror can be removed for replacement when necessary; or for use independently of the bag frame members.

the hand bag, as for instance when the owner of the hand bag desires to loan the mirror to another person without desiring such person to view the contents of the hand bag.

The link member 15 is mounted on the bracket arm 14 so that it normally rests in a substantially horizontal plane below the top of the bag frame member. Means are provided to swing the link member 15 about the pivot point 16, to elevate the mirror to the position shown in Fig. 2. In this instance, these means comprise a suitable spring device including a suitable cylinder or retainer 20 secured to the side member 21 of the frame 11, as indicated at 22. An operating rod 23 extends through the cylinder 20 parallel with the side member 21. This rod 23 has its upper end pivotally connected to the curved end of the link member 15, as seen at 24, an arcuate slot 25 being provided in the end portion of the link member 15.

To operate the rod 23, in this instance, an elliptical cam 26 is eccentrically secured to the frame member 12 at the hinge 13, this cam having a grooved outer edge 27 adapted to be traversed by the lower end of the rod 23. The cam 26 is set so that when the bag is open, and the mirror presented above the bag frame, as seen in Fig. 2, the rod 23 will rest on the base of the cam groove 27. A coiled spring 28 surrounds the rod 23 within the cylinder 20, this spring acting between the upper end of the cylinder 20 and a stop 29 provided on the rod 23, and normally being under slight compression.

During the closing movement of the bag, the opposite side frame member 12 causes the cam to rotate at the hinge 13, bringing the upper surface of the cam against the lower end of the rod 23 and moving the rod upward. This upward movement of the rod 23 causes the upper pivoted end of the rod to swing the link member 15, bringing the mirror 17 down within the bag frame. During the upward movement of the rod 23, a pin 33 secured to the rod enters a hole or slot 35 provided at the side frame member 21. This will hold the rod 23 in its upper position with the spring 28 under compression, and the mirror entirely within the confines of the bag. The bag frame can thus be opened to a normal extent without elevating the mirror, affording access to the bag for ordinary purposes. When it is desired to use the mirror, a finger piece 34 is manually operated to withdraw the pin 33 from the slot 35. In this position of the parts the rod 23 will descend, as seen at 32, under the influence of the spring 28, thus permitting the rod to draw the end 25 of the link member 15 downward, swinging the link 15 about the pivot 16, and causing the mirror 17 to assume an elevated position above the bag frame, as seen in Fig. 2.

When the mirror has been thus raised, the

user can hold the hand bag with extended mirror in one hand in any position, the other hand being free for other purposes; or, the hand bag may be allowed to rest on a table or other surface, leaving both hands free. After use of the mirror, it may be simply manually depressed to its normal position within the bag frame, where it will be locked at the slot 35; or the bag may be closed, the closing action of the frame members automatically causing the mirror to return to its normal latched position, as already described.

It is understood that instead of causing the mirror to swing in an arc during its raised movement, I may construct the link mechanism to elevate the mirror in a vertical plane or otherwise, within the scope of the invention as claimed.

The hereinbefore described construction admits of considerable modification without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

What I claim as new is:—

1. In combination with the U-frame of a hand bag or the like of an adjustable mirror attachment comprising a mirror support mounted at the upper part of one of the bag frame members, a mirror on said support, spring actuated means to elevate said mirror above the bag frame, and means at the hinge of the bag frame members to operate said spring actuated means.

2. The combination with the U-frame of a hand bag or the like of an adjustable mirror attachment comprising a swinging link pivoted at the upper part of one of the bag frame members, a mirror on said swingable link at one side of the pivotal joint, spring actuated means to engage the opposite end of said swingable link, said swingable link normally positioned within the bag frame, and means operative when the bag is open to release said spring actuated means to swing said mirror to a position outside the bag frame.

3. The combination with the U-frame of a hand bag or the like of an adjustable mirror attachment comprising a swingable link pivoted at the upper part of one of the bag frame members, a mirror on said link at one side of the pivotal joint, a spring actuated rod having one of its ends pivotally connected to said link, said link normally positioned within the bag frame, said spring actuated rod adapted to raise said mirror, and means dependent on the closing movement of the bag frame members to operate

said spring actuated rod to swing said mirror to a position within the bag frame.

4. The combination with the U-frame of a hand bag or the like, of an adjustable mirror attachment comprising a link member pivoted to one of the bag frame members, a mirror mounted at one end of said link member, said link member arranged to normally rest within the bag frame, and means to swing said link member about its pivot to elevate said mirror above the bag frame, said means comprising a spring pressed device connected to said link member and means to release said spring pressed device whereby 15 to swing said link member and present said mirror at an elevated position above the bag frame.

5. The combination with the U-frame of a hand bag or the like, of an adjustable mirror attachment comprising a link member pivotally mounted part way of its length to one of the bag frame members, a mirror mounted at one end of said link member, said link member arranged to normally rest within the bag frame, and means to swing said link member about its pivot to elevate said mirror above the bag frame, said means comprising a spring pressed operating rod mounted on said bag frame member, said rod having its upper end pivotally connected to said link member, the lower end of said rod having a pin and slot engagement with one of the bag frame members to release said spring pressed rod from said pin and slot engagement to present said mirror at an elevated position above the bag frame.

6. The combination with the U-frame of a hand bag or the like, of an adjustable mirror attachment comprising a link member pivoted part way of its length to one of the bag frame members, a mirror mounted at one end of said link member, said link member arranged to normally rest in a substantially horizontal position within the bag frame, and means to swing said link member about its pivot to elevate said mirror above the bag frame, said means comprising a spring pressed device connected to said link member and a cam device at the hinge of the bag frame members to operate said spring pressed device, means to release said spring pressed device, whereby to swing said link member and present said mirror at an elevated position above the bag frame, and means dependent on the closing movement of the bag frame members to return said mirror to its normal position.

7. The combination with the U-frame of a hand bag or the like, of an adjustable mirror attachment comprising a bracket at the upper part of one of the frame members, a link member pivotally mounted part way of its length to one of the bag frame members, a mirror mounted at one end of said link member, said link member arranged to normally rest in a substantially horizontal posi-

tion within the bag frame, and means to swing said link member about its pivot to elevate said mirror above the bag frame, said means comprising a spring pressed operating rod mounted on said bag frame member, said rod having its upper end pivotally connected to said link member, an elliptical eccentric cam to engage the lower end of said operating rod, means whereby said cam operates said spring pressed rod and hence said link member to position said mirror within the bag, and means to release said spring pressed operating rod to present said mirror at an elevated position.

8. The combination with the U-frame of a hand bag or the like, of an adjustable mirror attachment comprising a bracket at the upper part of one of the frame members, a link member pivoted to said bracket, a mirror at one end of said link member, said link member arranged to normally rest within the bag frame, means to swing said link member about its pivot to elevate said mirror above the bag frame, said means comprising an operating rod having its upper end pivotally connected to said link member, a cam device to engage said operating rod, spring pressed means to urge said rod in one direction, means whereby the opposite bag frame member rotates said cam during the closing movement of the hand bag, to compress said spring pressed means, means to hold said spring pressed means in operative position, and means to release said spring pressed means whereby said rod moves in the opposite direction and swings said link member to present said mirror at an elevated position above the bag frame.

9. The combination with a hand bag or the like, having opposite frame members of an adjustable mirror attachment comprising a bracket at the upper part of one of the frame members, a link member pivoted part way of its length to said bracket, a mirror mounted at one end of said link member, said link member arranged to normally rest within the bag frame, and means to swing said link member about its pivot to elevate said mirror above the bag frame said means comprising an operating rod mounted at the side of said bag frame member, said rod having its upper end pivotally connected to said link member and an elliptical cam mounted eccentrically at the hinge of the bag frame members, said cam having a grooved outer edge to receive the lower end of said operating rod, spring pressed means to urge said rod in a downward direction, means whereby the opposite bag frame member rotates said cam during the closing movement of the hand bag,

said cam adapted to raise said rod against said spring pressed means during said opening movement, means to hold said spring pressed means in operative condition, and means to release said spring pressed means

whereby said rod descends and swings said link member to present said mirror at an elevated position above the bag frame, said cam adapted to return said mirror to normal position during the closing movement of the bag.

In testimony whereof I hereby affix my signature.
